UNITED STATES PATENT OFFICE.

PHILIP MUELLER AND ANTON C. SCHUERMANN, OF DECATUR, ILLINOIS, ASSIGNEES TO
H. MUELLER MFG. CO., OF DECATUR, ILLINOIS, A CORPORATION OF ILLINOIS.

SELF-CLOSING COCK AND RECEPTACLE-ACTUATED OPENING MEANS THEREFOR.

1,095,984.

Specification of Letters Patent.

Patented May 5, 1914.

Application filed August 9, 1913. Serial No. 783,897.

To all whom it may concern:

Be it known that we, PHILIP MUELLER and ANTON C. SCHUERMANN, citizens of the United States, residing at Decatur, in the 5 county of Macon and State of Illinois, have invented new and useful Improvements in Self-Closing Cocks and Receptacle-Actuated Opening Means Therefor, of which the following is a specification.

10 This invention relates to self-closing cocks, more particularly to an improved structure of the cock and to improved means for opening the same.

Principally among the objects of this invention are—to provide a strong durable cock structure of the self-closing variety which is compact, takes up but small space, has relatively few working parts and in which access may be readily gained to the 15 parts for adjusting and renewing the same; and to provide means for opening the valve of the cock by merely placing a receptacle beneath the nozzle or outlet of the cock prior to actuating the same, the opening means 20 being provided with a guard for engagement with the receptacle to prevent the receptacle striking against the cock and chipping or breaking and to guide the receptacle into the correct position beneath the cock for 25 30 filling the receptacle.

Other objects and advantages of this invention will appear from the following detail disclosure of one embodiment of this invention, the same being illustrated in the accompanying drawings in which—

Figure 1 is a vertical longitudinal section through the cock. Fig. 2 is a detail fragmentary enlarged sectional view of the lower end of Fig. 1. Fig. 3 is a transverse section 40 taken on the line 3—3 of Fig. 2. Fig. 4 is a detail top plan view of the nozzle of the cock. Fig. 5 is a section taken on the line 5—5 of Fig. 4. Fig. 6 is a bottom plan view of the valve abutment hereinafter described. Fig. 45 50 55 7 is a side elevation of the improved cock and opening means therefor showing a receptacle about to be placed beneath the cock, the dotted lines showing the receptacle in position beneath the cock and showing the mechanism holding the cock open. Fig. 8 is an inner end elevational view of the cock and mechanism of Fig. 7, the shank of the cock being shown in section. Fig. 9 is a detail top plan view of the guard for engagement with the receptacle.

Referring to these drawings, 10 is a cock body open at its opposite ends and having an internally screw-threaded portion at its upper end to receive a detachable cap 11. The lower end of the body or casing 10 has an inturned flange 12 provided with a bead or raised portion at its inner edge constituting with the flange 12 a valve seat. Depending from the flange 12 is an annular wall 13 of reduced diameter as compared to the casing 10 and constituting a guide as hereinafter described. Above the flange or valve seat 12 the wall of the casing is thickened by inwardly extending ribs 14 extending up a short distance from the valve seat. The casing 10 has an exterior annular shoulder 15 at its lower end, formed by reason of the reduced size of the wall or guide 13. Threaded or otherwise suitably secured to the inner side of the casing or body 10, and adjacent to its upper end, is a shank 16 provided with a threaded portion 17 at its inner extremity, or with any other suitable means, for attaching the shank 16 to a source of fluid supply. The shank 16 communicates with the interior of the casing as may be clearly seen from Fig. 1.

Within the body 10 is located a two-part valve stem 18, 19. The part 18 is located in the upper end of the body 10 and has an enlarged head 20 at its lower end snugly fitting in the reduced portion of the casing 10 and adapted to move between the ribs 14. The head 20 is recessed in its underside to receive a suitable packing 21 for seating upon the valve seat 12. The packing 21 is held within the head 20 by the shoulder 22 formed upon the lower stem section 19, which section has a reduced threaded portion above the shoulder 22 adapted to pass through the packing 21, the head 20 and into the lower end of the stem 18 and engage in threaded relation with the head and the stem to hold the two valve-stem sections together. The lower section 19 extends from the shoulder 22 down through the valve seat 12 and carries upon its lower end an abutment or disk 23 fitting snugly within the wall or guide 13 and having a number of openings 24 therethrough to admit of the uninterrupted passage of the fluid from the body 10. In Fig. 6 a bottom plan view of the disk 23 is shown and wherein it will be seen that the disk has in its underside a diametrically extending kerf 25 adapted for

the reception of a screw driver or other suitable tool for turning the lower stem section 19 in assembling and disassembling the cock.

The valve, comprising the head 20 and packing 21, is normally held closed upon the seat 12 by a spring 26 surrounding the upper section 18 of the valve stem and bearing at its opposite ends respectively against the head 20 and the lower end of the cap 11, as clearly shown in Fig. 1. The cap 11 is hollow or is recessed as shown to accommodate the upper end of the stem section 18 to guide the stem in its movements and to admit of the lifting of the valve from the valve seat. The stem 18 is provided with a kerf or is given other suitable formation to accommodate a tool for holding the upper section 18 during the rotation of the lower section 19. Surrounding the lower end of the body 10 is a nozzle 27, the same comprising a sleeve having its inner diameter reduced at its lower end to snugly engage the wall or guide 13 and to provide a shoulder 28 adapted for engagement with the shoulder 15 to limit the upward sliding movement of the nozzle upon the body 10. The lower end of the nozzle 27 has an inwardly extending annular flange 29 located directly opposite the end of the guide 13 and carrying at its inner edge in circular relation a plurality of spaced apart fingers 30. The fingers 30 are offset inwardly from the flange 29, as shown to advantage in Fig. 4, and project up into the guide 13 and engage the inner side thereof. The fingers 30 are thus located in direct line with the edge of the disk or abutment 23 and are adapted to move the same when the nozzle 27 is moved up on the body 10. From Fig. 1 it will be noted that the shank 16 of the cock is provided with means for controlling the flow of fluid through the shank, the means in the present instance being disclosed as comprising a screw valve 31 threaded diametrically through the shank 16 and having a portion of one side cut away to provide a recess adapted to register with the passage through the shank 16. This screw valve 31 is adapted to be turned in order to register the recess more or less with the passage through the shank so as to regulate the normal flow of fluid through the cock. A screw plug 32 is threaded in the side of the shank 16 and is adapted to bind down upon the end of the screw valve 31. The screw plug 32 constitutes a lock to hold the valve 31 and the plug 32 have kerfs for the reception of a suitable tool adapted for turning these members.

Referring particularly to Figs. 7, 8 and 9, the opening means for the normally closed cock above described comprises a reversely E-shaped lever 33, the upper end of which is forked to provide a pair of arms 34 fitting

against the opposite sides of the cock body 10, and being suitably hinged thereto as at 35. The peculiar formation of the arm 33 offsets the same from the body 10 so that the body portion of the arm extends down beneath the shank 16 substantially parallel to the longitudinal axis of the cock body 10. The middle portion of the lever 33 is provided with a stop 36 adapted for engagement, as shown in Fig. 7, with the inner side of the body 10 or nozzle 27. The lever 33 projects down from the nozzle 27 and carries upon its lower end a guard such as shown in detail in Fig. 9. This guard comprises an arcuate strip 37 conforming substantially to the shape of one side of a receptacle, such as the glass shown at 38 in Figs. 7 and 8, and lies in a substantially vertical plane. The strip 37 is provided near its opposite ends with a pair of fingers 39 rising to a point near the lower end of the nozzle 27 and being there turned outwardly to provide projections or lips 40 adapted to engage the upper edge of the receptacle 38 and prevent the movement of the receptacle above the lips.

The upper forked end of the reversely formed E-shaped lever 33 connects at a point spaced inwardly from its pivotal connection 35 with the body 10, to the nozzle 27 by links 41. The links 41 are hinged at their lower ends upon the opposite sides of the nozzle 27 as at 42 and are hinged at their upper ends to the arms 34 of the lever 33 at points indicated at 43.

In operation fluid passes through the shank 16, its flow being regulated by the screw valve 31, into the body 10 of the cock. Normally the spring 26 holds the valve 20 to its seat 12 and the fluid is thereby prevented from escaping from the body.

From Fig. 7 it will be noted that when it is desired to draw off a quantity of fluid through the cock into the receptacle 38, the latter is placed against the guard or strip 37, the receptacle 38 being moved up toward the nozzle 27 until the upper edge of the receptacle strikes the lips 40. A pressure is now exerted upon the receptacle 38 to force it back under the nozzle 27 into the position disclosed in dotted lines in Fig. 7. This movement swings the lever 33 backwardly and turns the lever upon its pivotal supports 35 whereupon the links 41 are raised and cause the nozzle 27 to be drawn up upon the body 10. The position of the lever and the links in this latter position is shown in dotted lines in Fig. 7.

When the nozzle 27 is thus raised the fingers 30 of the nozzle move up in the guide 13 and strike the abutment 23, carrying the abutment up upon the further movement of the nozzle. The abutment 23 lifts the two-part valve stem against the tension of the spring 26 and thereby raises the valve 20

from its seat 12. Fluid in the body 10 now passes down about the sides of the valve head 20 in the chanings between the ribs 14, the fluid passing down through the valve 5 seat, the openings 24 in the abutment 23, and finally out through the lower end of the nozzle 27 into the receptacle. As soon as the desired quantity of fluid has been drawn off the receptacle 38 is drawn away from the 10 strip 37 and the lever 33 by its own weight, drops back into the normal position shown in full lines in Fig. 7 and the valve is automatically closed by the spring 26. The stop 36 limits the forward swinging movement of 15 the lever 33 and holds the nozzle 27 from falling from the body 10. It will be noted from Fig. 7 that when the receptacle 38 is pushed up against the lips 40 the glass is guided into its proper position beneath the 20 nozzle 27 by merely pushing inwardly upon the glass since the lever 33 is so hinged as to slightly raise the guard and carry the glass up about the lower end of the nozzle 27.

What is claimed is—

- 25 1. In a self closing cock, a movable nozzle for opening the cock, a lever hinged to the cock, a guard carried upon the end of the lever beneath the nozzle adapted to receive a receptacle and guide the same into position 30 beneath the cock, and links connecting the nozzle to the lever whereby the movement of the lever raises said nozzle to open the cock.
  2. In a self closing cock, a movable nozzle therefor adapted to open the cock, a re- 35 versely E-shaped lever hinged at its upper end upon the cock, a link connecting the lever to the nozzle to raise the latter upon the swinging of the lever, a guard carried upon the lower end of the lever beneath the cock 40 and adapted to receive a receptacle, said guard being adapted to guide the receptacle into position beneath the nozzle upon the in- ward swinging of said lever.
  3. In a self closing cock, a movable nozzle 45 therefor adapted to open the cock, a lever hinged upon the cock and having connection with the nozzle to move the same, and a guard carried upon the lower end of the lever and adapted to receive a receptacle and 50 guide the same into position beneath the nozzle as the lever is moved.
  4. In a self closing cock, a movable part for the cock adapted to open the same, a lever hinged upon the cock and having con- 55 nection with said movable part, a guard upon the end of the lever, and overhanging
- 60 lips carried upon the guard, said guard being adapted for the reception of a receptacle and said lips being adapted to engage the receptacle for limiting the upward sliding movement of the same in said guard.
- 65 5. In a self closing cock, a movable part adapted to open the cock, a lever hinged upon the cock and having connection with said movable part, a guard carried upon the lever adapted to receive one side of a receptacle thereagainst for swinging said lever, and means upon the guard for determining the position of said receptacle beneath the cock.
- 70 6. In a self closing cock, a nozzle movable upon the lower end of the cock and adapted to open the same, a lever hinged upon the upper end of the cock and extending down to a point beneath the nozzle, an arcuate strip carried upon the lower end of said lever for engagement against the side of a receptacle, upstanding fingers on said strip, lips carried upon the upper ends of said fingers for engagement with the upper edge of a receptacle, and links connecting said nozzle to said lever.
- 75 7. In combination with a self closing cock having a movable nozzle for opening the cock, a reversely E-shaped lever having its upper arm pivoted to said cock, a guard upon the lower arm of said lever arranged beneath said nozzle for the reception of a receptacle, the intermediate arm of said lever constituting a stop for engagement 80 against the side of said cock to limit the forward swinging of the lever, and a link connecting said nozzle to said lever whereby to move said nozzle upon the backward swing- 85 ing movement of said lever.
- 90 8. In a self-closing cock, a movable nozzle therefore adapted to open the cock, a lever hinged upon the cock and having connection with the nozzle to move the same, a guard carried on the lower end of the lever beneath the nozzle and receptacle engaging lips on the guard adapted to prevent the receptacle from moving upwardly and being broken against the nozzle.
- 95 9. In testimony whereof we have hereunto set our hands in presence of two subscribing witnesses.

PHILIP MUELLER.

ANTON C. SCHUERMANN.
